UNITED STATES PATENT OFFICE.

HARRY J. WILLIAMS, OF NEW HAVEN, ASSIGNOR OF ONE-HALF TO CHARLES L. LYON, OF MERIDEN, CONNECTICUT.

LEMON-SQUEEZER.

SPECIFICATION forming part of Letters Patent No. 473,043, dated April 19, 1892.

Application filed May 8, 1891. Serial No. 391,992. (No model.)

To all whom it may concern:

Be it known that I, HARRY J. WILLIAMS, of Meriden, in the county of New Haven and State of Connecticut, have invented certain new and useful Improvements in Lemon-Squeezers; and I do hereby declare the following to be a full, clear, and exact description of the same, reference being had to the accompanying drawings, forming a part of this specification, and to letters of reference marked thereon.

This invention has for its object to provide an improved squeezer for lemons, which shall be simple, powerful, and cheap; and the invention consists in certain novel details of construction and combinations and arrangements of parts to be hereinafter described, and pointed out particularly in the appended claims.

Referring to the accompanying drawings, Figure 1 is a perspective view of a lemon-squeezer constructed in accordance with my present invention. Fig. 2 is a longitudinal vertical section of the same. Fig. 3 is a detail perspective of the rotary reciprocating plunger and gear-wheel. Fig. 4 is a section of a modification.

Like letters of reference in the several figures indicate the same parts.

30 A indicates the housing or frame for the operating mechanism; B, the rotary reciprocating plunger, carrying at the lower end the movable cup C, and D indicates the handle which, through suitable gearing to be presently particularly described, imparts the reciprocating movement to the plunger.

The frame A is preferably formed integral with a supporting standard F, having a clamp formed by the wing f, and set-screw f', 40 adapted to secure the device to a table, counter, or other suitable support, while to the bottom of the standard and immediately below the plunger and movable cup is secured the stationary cup G, provided with a central cone G', of any approved pattern, adapted to co-operate with the movable cup to press the lemon placed between them.

The stationary cup G is provided with an offset g, fitting in a socket in the lower end 50 of the standard and held by a set-screw or

other suitable device, preferably, however, by the upper end of the glass-support hanger H, which is screw-threaded for the purpose. This hanger H has the glass-support h adjustably secured thereto below the stationary 55 cup, as shown.

In order to express the juice completely from the lemon, it is necessary to cause a slight rotation of the pressing surfaces with relation to each other, and in the present instance I accomplish this by giving the plunger and cup a slight rotation as they descend, which result can be accomplished by a number of mechanical expedients; but I prefer to form teeth on the plunger of some character with which a gear-wheel or other suitable device may be made to engage to turn the plunger on its own axis.

As shown in the drawings, and as I prefer to construct them, the teeth on the plunger are 70 inclined or formed into a spiral or worm, with which, as shown, both a stationary pin or projection and a gear-wheel having inclined teeth co-operate to give the desired rotary movement. The top of the plunger is provided with teeth inclined at a relatively steep angle, and the gear-wheel I, carried by the squared end d of the handle D and meshing therewith, is provided with teeth correspondingly inclined, the result of which is that 80 when the handle is moved in one direction or the other not only is the plunger raised or lowered, as the case may be, but it is given a strong tendency to rotate on the principle of the well-known "worm-gear."

To prevent the rotation of the plunger while traversing the upper portion of its stroke, its lower end has a flattened or cut-away portion M for co-operation with a pin N or equivalent projection on the frame, and 90 at the top of the flattened portion, or at the point where it is desired that the rotation shall begin, the body of the plunger is reduced, such reduced portion preferably taking the form of a spiral, forming teeth at an opposite 95 inclination to those on the upper end of the plunger. When the plunger descends, the pin or projection first encounters the flattened portion of the plunger, causing the lemon to be squeezed squarely. Then just 100

before the finish of the stroke the pin passes into the reduced portion or spiral and the plunger rotates one or more times, as desired, the rotation in the device shown being one and one-half times, causing a complete disintegration of the cellular structure of the lemon and the expulsion of all the juice.

- It is obvious that other well-known gearing may be employed to reciprocate and rotate the plunger. For instance, the upper end of the plunger may be a simple rack and the gear-wheel an ordinary gear, as shown in Fig. 4, with the inclined teeth at the bottom for giving the rotation, or the inclined teeth of the gear-wheel may be relied on entirely to co-operate with the inclined teeth of the plunger to give the desired rotation, without departing in the least from the present invention.
- The device as a whole is extremely simple and effective, there being no frail and complicated parts to get out of order or be broken by rough handling, and being adapted for ready application to a counter, table, or other support it is eminently adapted for household use or for use in bar-rooms where rapidity and effectiveness are absolute essentials.

Having thus described my invention, what I claim as new is—

1. In a lemon-squeezer, the combination, with the frame, the handle journaled therein, and a toothed wheel moved by the handle, having its teeth set at an angle, of the plunger journaled in the frame, with the inclined teeth thereon meshing with the teeth on the wheel, means, substantially as described, for automatically rotating said plunger as it descends, the cup on the plunger, and a lemon-support co-operating with the cup, substantially as described.
2. In a lemon-squeezer, the combination, with the frame, the handle journaled therein, the toothed wheel moved by the handle, having its teeth arranged at an angle, of the plunger journaled in the frame and having teeth thereon arranged at an angle corresponding to that of the teeth on the wheel, the pin or projection fitting in a recess in the plunger for preventing the rotation of the

plunger when raised, and a lemon-support, substantially as described.

3. In a lemon-squeezer, the combination, with the frame, of the movable plunger carrying the cup and having the inclined teeth thereon, the projection on the frame engaging said teeth to rotate the plunger as it descends, and a lemon-support, substantially as described.

4. In a lemon-squeezer, the combination, with the frame and handle journaled therein, of the plunger carrying the cup and having the oppositely-inclined teeth and pin-groove thereon, the projection on the frame engaging said teeth and groove to rotate the plunger as it descends, a wheel moved by the handle and having a worm-gear meshing with the teeth on the plunger, and a lemon-support, substantially as described.

5. In a lemon-squeezer, the combination, with the frame and handle, of the plunger having the oppositely-inclined spiral teeth thereon, and the cut-out portion merging into the space between the teeth at one end, the pin or projection on the frame co-operating with said cut-out portion and spiral, the toothed wheel moved by the handle, co-operating with the teeth at the opposite end of the plunger, and a lemon-support, substantially as described.

6. In a lemon-squeezer, the combination, with the stationary cup, the plunger, and means, substantially as described, for reciprocating the plunger, of the spiral, and the projection co-operating therewith to rotate the plunger while being reciprocated, substantially as described.

7. In a lemon-squeezer, the combination, with the stationary cup, the plunger having the teeth extending entirely around the same, and the gear-wheel meshing therewith, having the handle for reciprocating the plunger, of the spiral and the projection co-operating therewith to rotate the plunger while being reciprocated, substantially as described.

HARRY J. WILLIAMS.

Witnesses:

L. TREDINNICK,
A. L. STEVENS.

It is hereby certified that the residence of the patentee in the grant and in the head of the printed specification of Letters Patent No. 473,043, granted April 19, 1892, upon the application of Harry J. Williams, for an improvement in "Lemon-Squeezers," was erroneously written and printed "New Haven, Connecticut"; whereas said residence should have been written and printed *Meriden, Connecticut*; and that the said Letters Patent should be read with this correction therein that the same may conform to the record of the case in the Patent Office.

Signed, countersigned, and sealed this 3d day of May, A. D. 1892.

[SEAL.]

CYRUS BUSSEY,
Assistant Secretary of the Interior.
